CLAIM

The ornamental design for a medication inhaler spacer, as shown and described.

DESCRIPTION

FIG. 1 is a perspective view of a medication inhaler spacer showing my new design;

FIG. 2 is a top plan view thereof;

FIG. 3 is a bottom plan view thereof;

FIG. 4 is a right side elevational thereof, the left side being a mirror image; and,

FIG. 5 is an elevational view of one end thereof, the opposite end being a mirror image.
